UNITED STATES PATENT OFFICE

2,046,800

STRAW HOPPER AND DELIVERY MECHANISM FOR STRAW PACKAGING MACHINES AND THE LIKE

John J. Toolan, Chicago, Ill.

Original application July 6, 1934, Serial No. 734,056. Divided and this application April 25, 1935, Serial No. 18,221

19 Claims. (Cl. 226—2)

The present invention relates to machines for packaging straws in envelopes and it particularly relates to the straw hopper and the means to feed the straws from the hopper and assemble them into position for insertion in the wrapper.

The invention has for an object to provide an improved straw hopper and feeding means for feeding the straws in selected groups (pairs in the embodiment illustrated) to the straw receiver.

Further, it is an object to provide any suitable safety device for stopping the machine if the hopper becomes empty or if the straws pile up in the filling or delivery mechanism in a manner which would tend to jam the machine and cause it to deliver defective packages.

Other objects will in part be obvious and in part be pointed out hereinafter.

To the attainment of the aforesaid objects and ends, the invention still further resides in the novel details of construction, combination and arrangement of parts, all of which will be first fully described in the following detailed description, and then be particularly pointed out in the appended claims, reference being had to the accompanying drawings, in which:

Figure 1 is a plan view of so much of a straw packaging machine as is necessary to illustrate my present invention.

Figure 2 is a front elevation of the parts shown in Figure 1.

Figure 3 is a rear view of the parts shown in Figure 1.

Figure 4 is a cross section on the line 4—4 of Figure 3 looking in the direction of the arrow.

Figure 5 is a cross section on the line 5—5 of Figure 3 looking in the direction of the arrow.

Figure 6 is an edge elevation of one of the straw selector wheels.

Figure 7 is a side elevation of the same.

Figure 8 is a detail perspective view of the funnel end of a straw receiving slide.

Figure 9 is a detail perspective view of the other end of the straw receiving slide.

Figure 10 is a detail end elevation of the slide and its retainer, a part being broken away.

Figure 11 is a detail perspective of the pushing end of the straw inserting push-bar.

Figure 12 is a detail perspective of one of the cross-heads.

Figure 13 is a detail perspective view of one of the adjustable pivot plates.

Figure 14 is a detail elevation of the detachable block of one of the safety devices.

Figure 15 is a detail view of part of the drive gearing.

Figure 16 is a circuit diagram of the safety devices showing how they cooperate with the driving motor.

In the drawings I have illustrated only so much of my complete machine which is embodied in my original application filed July 6, 1934, Serial No. 734,056 as is necessary to a clear understanding of the present invention, the present application being a division of my said original application. Like numerals of reference are used throughout the drawings to indicate like parts in all of the figures.

The machine comprises a base 1 which is supported on suitable standards 2. Held in a bearing 4 in an end standard 3, and in a corresponding bearing 104x in a standard 104, is the main shaft 5 of the package and straw assembling units, shown particularly in Figures 1, 2 and 3 of the drawings. Secured to the shaft 5 are disks 7, 8, 9, 10, 11 and 12, and mounted on the shaft 5 is a barrel-cam 18 having a hub portion on which is rotatably mounted a ring-like disk 6. The cam is held from rotating by a locked screw 35. Pairs of guide bars 13 are secured to and between the disks 6 and 7, constituting therewith a rotatable drum-like skeleton. In the embodiment illustrated there are six pairs of guide bars disposed sixty degrees apart. The bars 13 have longitudinal slots 14 constituting guideways for the cross-heads 15 which are mounted to be reciprocated along the guide bars by means of rollers 20 which engage in a cam groove 19 of the cam 18. Secured (preferably adjustably) on each cross-head 15 is a pivot plate 21 which has a stud 17 to which a push-bar 16 is pivoted.

Mounted in radial slots in the disks, 1, 8, 9 and 10 is a set of straw receiving slides 22 each of which has a longitudinal straw receiving groove 23 of a width to take the number of straws that the machine is designed to place in one package (two straws to the package in the illustrated embodiment of my invention. Each slide 22 has grooves 24 (forming with the groove 23 a T- slot). A push-bar 16 operates in each groove 23. The bar 16 has suitably located wings 30 in the grooves 24 to guide and steady the bar as it is moved longitudinally in the groove 23.

In order to hold the slides 22 in place on the disks 1, 8, 9 and 10 retainers 29 are secured to the disks 8, 9 and 10. These retainers (see Figures 2, 9, and 10) have fingers 28 which enter longitudinal grooves 25 in the slides 22 as shown.

At the front end of each slide is secured a plate 55

26 which carries a funnel member 27 that is designed to be inserted in one open end of a wrapper W and through which funnel the straws S are passed into the wrappers. Each slide 22 is 5 also provided with a pair of spaced cross-grooves 31 (see Figures 2 and 8), into and through which the lips 172x are passed so as to ensure an even lay of the straws in the grooves and prevent, as far as possible, the straws falling out of parallelism when being delivered to the grooves from the chute.

10 The front end of each push-bar 16 is provided with a number of prongs 32 (the number depends on the number of straws to be placed 15 in a package). These prongs 32 are adapted to enter an open end of the straw and hold the same to move simultaneously forward through the funnel 27 into the wrapper W with which it is cooperating.

20 The slide 22 is given a slight longitudinal stroke, enough to bring the funnel 27 into and remove it from a wrapper W, by means of a cam 33 in the cam 18 with which groove a roller 34 on each slide engages.

25 A gear 142 on the shaft 5 meshes with a gear 143 on the straw selector shaft 144, which gear 143 in turn meshes with an idler pinion 145 that 30 is secured to a larger gear 146, the pinion 145 and the gear 146 rotating as one on a stub shaft 147 (see Figure 15). The gear 146 meshes with a gear 148 on the shaft 133.

The straw delivery and feeding mechanism

35 The mechanism for delivering or feeding the straws from the hopper 158 to the slides 22 is best shown in Figures 1 and 4, by reference to which it will be seen that a pair of straw selector wheels 149 (see Figures 4, 6 and 7) have adjustable spring advanced fingers 150 whose lugs 151 are engaged by adjustable finger plates 154 that 40 are secured to the wheels 149 by screws 155. The selector fingers 150 slide in radial slots 152 which contain the springs 153.

45 In order to agitate and break apart the straws within the hopper 158 and prevent them from jamming, I provide a rocking shaft 160 that carries a plate 159 which constitutes the back of the hopper. The shaft 160 is rocked by an arm 161 having a roller 162 that engages a cam 163 on the straw feeding shaft 164.

50 The shaft 164 carries sets of brushes 165 which operate to feed the straws S forwardly along the chute-way 172-173 (see Figure 4). The shaft 164 carries a loose pulley 166 having a pawl 167 55 to engage a ratchet 168 fixed to shaft 164, the shaft having a hand wheel 169 by which it may be turned manually, if and when desired.

55 The hopper 158 is supported on standards 170 and it also carries brackets 171 having bearings 60 for the shaft 164.

The straws are held down on the chute portion 172 by the plates 173 (see Figures 1 and 4) which plates are connected by a cross bar 174, the plates being carried by the hopper 158. The 65 plates 173 have straw check members 175 at their outer ends which, together with the lips 172x on the chute 172, form a throat through which the straws are delivered in selected number to the grooves 23 of the slides 22.

70 A pulley 176 on the shaft 133 drives the loose pulley 166 by means of a belt 177.

The straws are held from falling out of the grooves 23 by guide 156 carried on suitable supports 157 (see Figures 3 and 4).

75 In order to stop the machine as the hopper be-

comes empty or the stream of straws along the chute 172 is interrupted, I provide a safety device consisting of a support 180 carrying a block of insulation 181 in which is held a live contact 182. The contact 182 is adapted to be engaged by a 5 grounded contact 186 on the arm 185 of a lever that is pivoted at 184 and has a foot 183 whose heel is adapted to engage the straws S to keep the contacts separated while the flow of straws is normal. The live contact 182 leads to a relay 10 365 which, when the circuit is closed, opens the motor circuit, as will later more fully appear.

15 188 designates a pair of fixed straw retaining fingers carried on a rod 187. 189 designates a safety rocker arm which is provided with a straw 15 engaging foot 190 having a bevelled edge 191 to ride over straws and over the periphery of the disks 8 and 9. 192 designates a bell crank latch which is pivoted at 193 and is adapted to be engaged by a latch releasing arm 194 (see Fig. 4). 20 A cam 195 serves to move the arm 189 to a position with respect to the straw drum so as to move foot 190 out of contact with the straws so as to preserve the straws from pressure tending to mash them. If no straws are present arm 25 194 will act before cam 195 does.

196 is a safety rocker arm that is pivoted on the rod 187 and carries an electrical contact 197 on its insulated portion 198 there being a stop 199 provided to limit the rocking movement in 30 one direction. 200 designates a grounded contact (see Figures 4 and 16) which cooperates with the contact 197 to close the circuit of the relay 365 when member 196 passes an empty straw slide.

35 201 indicates an insulated block on the rocker arm 189, the insulated block carrying an electrical contact 202 which cooperates with a pivoted circuit closing member 344, this member having a notch 345 to cooperate with the latch 192, a 40 spring 346 being provided tending to draw the member 344 toward the latch 192. The weight of the arm 189 and its parts augmented by a spring 189x (see Figure 4) serves to hold the arm with its foot 190 normally in light contact 45 with the drum 9.

Operation

Now refer to Figures 1, 3, and 4. As will be seen by reference to Figure 4, as the straw receiving 50 50 drum-like unit, composed of the disks 8, 9, and 10 and parts carried thereby, moves in the direction of the arrow on the disk 9 in Figure 4 the selector fingers 150 at the right in Figure 4 will take the first two straws and deliver them into the groove 55 23 of the straw receiving slide 22 just beneath the same. The straws are fed down the chute 172 by the brushes 165, aided by gravity. As soon as the straws have been placed in the receiver 22, the push-bar 16 cooperating with that receiver 60 will be advancing to enter its projections 32 into the adjacent ends of a pair of straws. In the meantime the cam 33 will have advanced the straw carrier 22 to insert its funnel 27 into the wrapper which has lined up with it so that as the 65 movement of the machine continues the cam-way 19 will advance the push bar 16 to deliver the pair of straws through the funnel 27 and insert the straws completely in the wrapper by the time the unit under discussion reaches the lower left hand 70 position in Figure 4 and from that time on the push bar 16 recedes so that by the time the unit 22 under discussion reaches the position at the lower right in Figure 4 the bar 16 will have been fully withdrawn.

If no straws are deposited in a groove 23 as soon as that groove comes opposite the foot 190 that foot will drop into the groove thereby lowering rocker arm 189 to bring the latch 192 into the path of the releasing arm 149 which will trip the latch and permit the member 344 to swing to the dotted line position shown in Figure 4, thereby closing the circuit and effecting a stoppage of the motor.

ceive a determined number of straws, a chute to convey straws from said hopper to said bars, means to advance the straws along said chute from the hopper to the straw receiver, means to separate a selected number of straws in the chute from the remainder and place them in the grooves of said bars as the bars arrive at the delivery end of the chute, and power applying mechanism to operate the aforesaid parts, said bars having transverse grooves intersecting the straw receiving grooves and said chute having lips to enter said transverse grooves as the bars pass to guide the straws from the chute into place in the bars.

said power applying when the hopper becomes empty.

7. In a straw wrapping machine, a straw hopper, a rotatable straw receiver comprising a drum-like structure having peripheral grooves, longitudinally movable straw receiving bars located in said grooves, said bars each having a groove of sufficient cross sectional area to receive a determined number of straws, a chute to convey straws from said hopper to said bars, means to advance the straws along said chute from the hopper to the straw receiver, means to separate a selected number of straws in the chute from the remainder and place them in the grooves of said bars as the bars arrive at the delivery end of the chute, power applying mechanism to operate the aforesaid parts, said bars having transverse grooves intersecting the straw receiving grooves and said chute having lips to enter said transverse grooves as the bars pass to guide the straws from the chute into place in the bars, and means to stop the action of said power applying mechanism when the hopper becomes empty.

8. In a straw wrapping machine a straw hopper, a rotatable straw receiver comprising a drum-like structure having peripheral grooves, straw receiving bars located in said grooves, said bars each having a groove of sufficient cross sectional area to receive a determined number of straws, a chute to convey straws from said hopper to said bars, means to advance the straws along said chute from the hopper to the straw receiver, means to separate a selected number of straws in the chute from the remainder and place them in the grooves of said bars as the bars arrive at the delivery end of the chute, power applying mechanism to operate the aforesaid parts, said last-named means comprising disks in rolling contact with the drum-like structures, yieldable fingers carried by said disks to engage the straws at the end of the chute and convey the selected number to the straw receiving bar adjacent thereto, said bars having transverse grooves intersecting the straw receiving grooves, said chute having lips to enter said transverse grooves as the bars pass to guide the straws from the chute into place in the bars, and means to stop the action of said power applying mechanism when the hopper becomes empty.

9. In a straw wrapping machine, a straw hopper, a rotatable straw receiver comprising a drum-like structure having peripheral grooves, longitudinally movable straw receiving bars located in said grooves, said bars each having a groove of sufficient cross sectional area to receive a determined number of straws, a chute to convey straws from said hopper to said bars, means to advance the straws along said chute from the hopper to the straw receiver, means to separate a selected number of straws in the chute from the remainder and place them in the grooves of said bars as the bars arrive at the delivery end of the chute, power applying mechanism to operate the aforesaid parts, and means to stop the action of said power applying mechanism if less than the required number of straws is delivered to the respective bars.

10. In a straw wrapping machine, a straw hopper, a rotatable straw receiver comprising a drum-like structure having peripheral grooves, longitudinally movable straw receiving bars located in said grooves, said bars each having a groove of sufficient cross sectional area to receive a determined number of straws, a chute to convey straw

from said hopper to said bars, means to advance the straws along said chute from the hopper to the straw receiver, means to separate a selected number of straws in the chute from the remainder and place them in the grooves of said bars so the bars arrive at the delivery end of the chute, power applying mechanism to operate the aforesaid parts, means to stop the action of said power applying mechanism when the hopper becomes empty, and means to stop the action of said power applying mechanism if less than the required number of straws is delivered to the respective bars.

11. In a straw wrapping machine, a straw hopper, a rotatable straw receiver comprising a 15 drum-like structure having peripheral grooves, longitudinally movable straw receiving bars located in said grooves, said bars each having a groove of sufficient cross sectional area to receive a determined number of straws, a chute to convey straws from said hopper to said bars, means to advance said straws along said chute from the hopper to the straw receiver, means to separate a selected number of straws in the chute from the remainder and place them in the grooves of said bars as the bars arrive at the delivery end of the chute, power applying mechanism to operate the aforesaid parts, and means to stop the action of said power applying mechanism if more than the requisite number of straws is placed in said bars or the straws in a bar become displaced 20 25 30

12. In a straw wrapping machine, a straw hopper, a rotatable straw receiver comprising a drum-like structure having peripheral grooves, longitudinally movable straw receiving bars located in said grooves, said bars each having a groove of sufficient cross sectional area to receive a determined number of straws, a chute to convey straws from said hopper to said bars, means to advance the straws along said chute from the hopper to the straw receiver, means to separate a selected number of straws in the chute from the remainder and place them in the grooves of said bars as the bars arrive at the delivery end of the chute, power applying mechanism to operate the aforesaid parts, means to stop the action of said power applying mechanism when the hopper becomes empty, and means to stop the action of said power applying mechanism if more than the requisite number of straws is placed in said bars or the straws in a bar become displaced. 35 40 45 50

13. In a straw wrapping machine, a straw hopper, a rotatable straw receiver comprising a drum-like structure having peripheral grooves, longitudinally movable straw receiving bars located in said grooves, said bars each having a groove of sufficient cross sectional area to receive a determined number of straws, a chute to convey straws from said hopper to said bars, means to advance the straws along said chute from the hopper to the straw receiver, means to separate a selected number of straws in the chute from the remainder and place them in the grooves of said bars as the bars arrive at the delivery end of the chute, power applying mechanism to operate the aforesaid parts, means to stop the action of said power applying mechanism if less than the required number of straws is delivered to the respective bars, and means to stop the action of said power applying mechanism if more than the requisite number of straws is placed in said bars or the straws in a bar become displaced. 51 61 71

14. In a straw wrapping machine, a straw hopper, a rotatable straw receiver having peripheral grooves of such cross sectional area as to receive 7.

radially a definite number of straws, said grooves being open at their ends to deliver the straws in a direction parallel to the rotation axis of the receiver, a straw conveying chute extending from the hopper to the rotatable receiver for delivering straws to said grooves, means to advance the straws along said chute from the hopper to the straw receiver, and means for separating a selected number of straws in the chute from the remainder and laying them into the grooves of said rotary receiver as said grooves arrive at the delivery end of the chute, and power applying mechanism to operate the aforesaid parts.

15. In a straw wrapping machine, a straw hopper, a rotatable straw receiver having peripheral grooves of such cross sectional area as to receive radially a definite number of straws, said grooves being open at their ends to deliver the straws in a direction parallel to the rotation axis of the receiver, a straw conveying chute extending from the hopper to the rotatable receiver for delivering straws to said grooves, means to advance the straws along said chute from the hopper to the straw receiver, and means cooperating with the chute and with the rotatable receiver for separating a selected number of straws in the chute from the remainder and laying them into the grooves of said rotary receiver as said grooves arrive at the delivery end of the chute, and power applying mechanism to operate the aforesaid parts.

16. In a straw wrapping machine, a drumlike structure comprising a set of rotatable disks mounted on a shaft to rotate in unison, a plurality of bars mounted at the peripheries of said disks and extending from one disk to the other, said bars having straw receiving peripheral grooves intersected by cross grooves; a straw hopper; a chute for conveying straws from the hopper to said straw receiving grooves, said chute including lips to enter and pass through said cross grooves as the shaft rotates, and means selectively to separate a number of straws in the chute from the remainder and place the selected straws in the straw receiving grooves as they arrive at the delivery end of the chute; and power applying mechanism to operate the aforesaid parts.

17. In a straw wrapping machine, a drum-like structure comprising a set of rotatable disks mounted on a shaft to rotate in unison, a plurality of bars mounted at the peripheries of said disks and extending from one disk to the other, said bars having straw receiving peripheral grooves intersected by cross grooves; a straw hopper; a chute for conveying straws from the hopper to said straw receiving grooves, said chute including lips to enter and pass through said cross grooves as the shaft rotates; means selectively to separate a number of straws in the chute from the remainder and place the selected straws in the straw receiving grooves as they arrive at the delivery end of the chute; and means effecting continuous rotation of said drum-like structure and of said means to separate.

18. In a straw wrapping machine, a straw hopper; a rotatable straw receiver comprising a drum-like structure having peripheral straw receiving grooves each of sufficient cross sectional area to receive a definite number of straws; a chute to convey straws from said hopper and deliver the same to said grooves; means to advance the straws along the chute; rotatable disks adjacent the periphery of said receiver and yieldable fingers carried by said disks to separate selected numbers of straws from the remainder in the chute and convey the selected numbers of straws to said straw receiving grooves; and power applying means to operate the aforesaid parts.

19. In a straw wrapping machine, a straw hopper, a rotatable straw receiver having peripheral pockets, a chute to convey straws from said hopper to said receiver, means to advance straws along said chute from said hopper to said receiver, means to separate a selected number of straws in the chute from the remainder and place them in said pockets as the pockets arrive at the delivery end of the chute, said means including a rotatable disk adjacent the drum, yieldable fingers carried by said disk to engage the straws adjacent the end of the chute and convey the selected number to the pocket adjacent thereto, and means to actuate the aforesaid parts.

JOHN J. TOOLAN.
